UNITED STATES PATENT OFFICE.

LOUISA E. IRWIN, OF LONDON, ONTARIO, CANADA.

BABY'S STOCKING.

No. 872,517.

Specification of Letters Patent.

Patented Dec. 3, 1907.

Application filed August 21, 1906. Serial No. 331,525.

To all whom it may concern:

Be it known that I, LOUISA E. IRWIN, a subject of the King of Great Britain, and a resident of the city of London, in the county 5 of Middlesex, in the Province of Ontario, Canada, have invented a new and useful Baby's Stocking, of which the following is a specification.

This invention relates to coverings for 10 the feet and the lower part of the legs of a baby. And in its simplified form this invention consists essentially of a stocking the body of which is formed with a foot portion and a leg portion, and a flexible 15 band encircling, or extending around the foot portion, crossed at the instep and encircling or extending around the leg portion. To this it is proposed to add a loop on the 20 underside of the foot portion and a loop on the rear of the leg portion, but a single loop may be used at either position, for more positively holding the flexible band in place under certain circumstances. Though the 25 stocking owing to its contour, together with the flexible band encircling or extending around the foot and leg portions and crossed at the instep, will answer all purposes, and be effective in the holding of the stocking in place, it is obvious that various contingencies 30 and conditions may confront the user and the addition of these loops at the rear of the leg portion and at the bottom of the foot portion are to meet these contingencies. The stocking with the flexible band will be 35 practically sufficient, and the addition of the loops to the stocking are used simply from a precautionary standpoint, to meet the case where loose stockings are used, or in the case of fat babies, or where babies rub their feet 40 together, and on whom it is almost impossible, under ordinary circumstances, to keep the flexible bands in place or the stockings on their feet, or lower part of their legs. All of which will be more particularly described 45 with reference to the accompanying drawings wherein;—

Figure 1 is a view of a stocking embodying my invention.

In the accompanying drawings;—the number 50 10 designates a baby's stocking, and, *a*, the leg portion, and, *b*, the foot portion thereof.

11 designates a loop with which the rear of the leg portion, *a*, is provided, and 12 a loop with which the bottom of the foot portion, *b*, is provided.

13 designates a ribbon or flexible band which encircles or extends around the foot portion, *b*, of the stocking as shown at, *c*, crossed at the instep, *d*; and encircles or 60 extends around the leg portion, *a*, of the stocking as shown at, *e*, and, *f*, and its ends secured together at the front of the leg portion, *a*, as shown at, *g*; and said flexible band is shown as encircling or extending 65 around the foot portion, *b*, of the stocking once, and the leg portion, *a*, twice, but it may extend around said foot and said leg portions of said stocking one or any number of times, and its ends secured together, 70 at any point at the front, rear or side of the leg portion or at the top, bottom or side of the foot portion.

The loops 11 and 12 will be effective in holding the flexible band 13 in place against 75 any possibility of it becoming disengaged from the stocking, in the case of loose stockings or in the case of fat babies, or in the case where babies rub the sides of their feet together, and on whom under ordinary circumstances it is almost impossible to keep the stockings on their feet or on the lower part of their legs.

The practical advantages of a stocking constructed substantially as shown and described are;—that it may be readily and easily secured in place, and when secured in place, will be securely held against any possibility of becoming accidentally kicked, or rubbed off or otherwise disengaged from the 90 foot of the wearer, one when secured in place will be easy and comfortable on the wearer, as the flexible band is free to move lengthwise throughout its whole length and will give with each movement of the foot, at the 95 same time by untying the ends of the flexible band the stocking may be readily and easily removed; and one also that will be simple, durable and inexpensive to supply.

Having thus described my invention, I 100 claim;—

As a new article of manufacture, a stocking embodying a leg portion and a foot portion, a keeper carried by the leg portion adjacent

the juncture of the latter with the foot portion, a keeper carried by the bottom of the foot portion substantially midway between the ends of said foot portion, and a flexible
5 band passed through said loops and wrapped around the foot portion and leg portion of the stocking.

In testimony whereof, I have signed in the presence of the two undersigned witnesses.

LOUISA E. IRWIN.
